UNITED STATES PATENT OFFICE.

DANIEL L. TOWER, OF BROOKLYN, NEW YORK.

FOLDING GUARD FOR REVOLVERS.

SPECIFICATION forming part of Letters Patent No. 366,531, dated July 12, 1887.

Application filed October 19, 1886. Serial No. 216,633. (No model.)

To all whom it may concern:

Be it known that I, DANIEL L. TOWER, of Brooklyn, in the county of Kings and State of New York, have invented a new and useful

5 **Folding Guard for Pistols;** and I do hereby declare that the following is a full and exact description thereof, reference being had to the accompanying drawings, and to the letters of reference marked thereon, making a part of 10 this specification, in which—

Figure 1 is a side elevation of a pistol constructed with my improved folding guard; and Fig. 2 is a detached sectional view of the guard, illustrating its folding attachment.

15 It has been found very desirable in the construction of pistols, and especially self-cocking revolvers, to provide, in connection with the trigger-guard, a supporting-piece to be engaged by the second finger, so as to steady 20 the pistol in taking aim, leaving the first finger free to pull the trigger. This object has hitherto been attained by means of a projection formed integrally with the guard and adapted by its position and form to afford a 25 suitable support for the second finger; but such a projection from the guard, while suitable in every respect as a means for steadyng the pistol, becomes very objectionable in connection with pocket or holster pistols, be- 30 cause of the room which it takes up and its liability to catch, preventing thereby a ready withdrawal of the weapon when required for use.

The object of my invention is to secure in 35 a pocket or holster pistol all the advantages of a holding-piece for the second finger, to serve as a steadyng or supporting guard, without the objectionable feature of a projection which will require additional room in the pocket or 40 holster and be liable to become caught and entangled in its withdrawal therefrom. This object is attained by the combination, with the ordinary trigger-guard, of a supporting-piece so pivoted as to admit of being folded 45 up when not in use and present no projecting point or surface outside of the guard, but which may be readily and quickly swung out to project in a suitable position to furnish a hold and support for the second finger, whereby 50 the pistol may be steadied in the hand.

In the accompanying drawings, A repre-

sents the trigger-guard of a pistol. This trigger-guard may be of any approved form, and is attached to the pistol to partially encircle the trigger in the customary manner.

55

B represents a steadyng-piece consisting of a rod or bar bent at one end nearly at a right angle, so as to present thereby a longer arm, C, and a shorter arm, D, as clearly shown in Fig. 2. An extended aperture or slot, E, is 60 cut in the rear bent portion of the guard-plate A, to receive the bent portion of the steadyng-piece B, which being fitted therein is hinged thereto by means of a transverse pivot-pin, F. The position of the pivot-pin 65 is so adjusted with reference to the length of the shorter arm, D, of the steadyng-piece B that when said piece is swung out in a line coinciding with that of the rear bar, G, of the guard, as shown in Fig. 2 and by dotted lines, 70 Fig. 1, the outer end of the arm D will strike against the guard at the end of the slot, and thereby prevent a further movement of the steadyng-piece out from the guard.

The slot E is so extended above the pivot- 75 pin F as to form a recess, within which the shorter arm, D, of the steadyng-piece B may enter and be inclosed when its longer arm, C, is swung up against the lower bar, H, of the guard; and this lower bar, H, is recessed 80 on its outer side to receive and partially inclose said longer arm when it is thus closed against it.

The folding steadyng-piece B is so shaped that when its longer arm is folded against 85 the guard, as is shown in positive lines, Fig. 1, the entire piece will conform substantially therewith throughout its length and be partially or wholly concealed therein, and will present no material projection therefrom.

90

For use, when the pistol is to be fired, the steadyng-piece B is readily swung out into position in a right line with the rear bar, H, of the guard, as shown in Fig. 2, so as to constitute virtually an extension thereof in a 95 form adapted to engage neatly the second finger of the hand holding the pistol, the first finger being in position to engage the trigger, as shown by dotted lines in Fig. 1.

It is evident that a stop, D, for the outward 100 movement of the steadyng-piece B may be provided in the form of an offset from the

pivoted portion thereof at other points than that illustrated, and I contemplate the use of such a stop in any position thereof.

I claim as my invention—

- 5 1. The combination, with a pistol and its trigger-guard, of a steadyng-piece, substantially as described, pivoted thereto to swing out therefrom and provided with an offset or stop to limit its movement, substantially in the manner and for the purpose herein set forth.
- 10 2. The combination, with the trigger-guard

A, of the hinged steadyng-piece B, folding against the guard and provided with a stop, D, to stay it when opened out, substantially in 15 the manner and for the purpose set forth.

In testimony whereof I have signed my name to this specification in the presence of two subscribing witnesses.

DANIEL L. TOWER.
